H. F. HICKS,

Cotton Press.

No 29,341.

Patented July 24, 1860.

UNITED STATES PATENT OFFICE.

HORATIO F. HICKS, OF GRAND VIEW, INDIANA, ASSIGNOR TO HICKS BROTHERS, OF SAME PLACE.

IMPROVED COTTON AND HAY PRESS.

Specification forming part of Letters Patent No. 29,341, dated July 24, 1860.

To all whom it may concern:

Be it known that I, HORATIO F. HICKS, of Grand View, Spencer county, Indiana, have invented a new and useful Cotton and Hay Press; and I hereby declare the following to be a full, clear, and exact description of the same, reference being had to the accompanying drawings, making part of this specification.

The invention has for its object the effectual packing and pressing of cotton, &c., with a less consumption of labor, time, and space than heretofore.

In the accompanying drawings, Figure 1 is an axial section of a machine embodying my improvements. Fig. 2 is a cross-section on line *z z*. Fig. 3 is a perspective view of a detached part of the machine.

A frame, A, contains a vertical press-box about twelve feet high. The lower half of this box has four stationary sides, B, immediately above which the box is formed by L-shaped doors C, whose shorter leaf *c'* is hinged to the free edge of the longer leaf *c*, which leaf is hinged to the frame A. The uppermost portion of the box is closed on three sides by boards D, and is open on the fourth side to communicate with a trough or hopper, through which the cotton is supplied to the press. The free edge of the shorter leaf *c'* of each door is supported, when closed, by a shoulder on the long leaf of the opposite door, which itself is supported by a rabbet, *c''*, in the frame, customary catches, X, being employed to hold the doors shut. At or near the bottom of the frame A is a horizontal platform, F, perforated at center to hold the nut G, whose upper flange is supported upon the rollers *h* of a circular truck, H. I is the main screw, (of six inches pitch,) surmounted by a piston, J, which fits the box B. Attached to the lower part of the nut G are sweeps K, by which the machine is driven. Attached also to the lower portion of the nut or to the sweeps is a cylindrical ring, L, from whose concavity project spiral flanges M M'. N is a follower occupying the upper part of the box, and connected rigidly with a rod, O, which terminates below in a sliding section, O', provided with a roller, P, which, when the rod is extended, rests upon the flange M, and in the operation of packing is confined between the two flanges M M', so as to produce

a positive motion of the follower, as will be hereinafter explained. A tightening-screw, Q, enables the two sections of the rod to be securely attached to each other. R are catches, which serve to hold the follower stationary while the machine is to be used for pressing. Rollers S prevent the vertical displacement of the ring L. T are hinged flanges, which permit the descent but oppose the return of the cotton in packing.

Operation: The piston and follower being in their upper positions, the rods O O' being united, the roller P, resting upon the flat upper portion, *m*, of the flange M, and the doors C closed, the upper portion of the box between the piston and follower is supplied with cotton from the hopper. The ring L and nut G being now moved in direction of red arrow, a single rotation acts to lower the piston six inches, and at the same time to lower the follower three and one-fourth feet, thus packing or compressing about three feet of cotton into the space of about six inches, which the depression of the piston has left in the upper portion of the stationary part B of the box. A further rotation serves to elevate the follower for another charge, when the same movements are repeated until the entire space inclosed between the sides B (about six feet deep) is packed with cotton. The follower being now secured in its lowest position by the catches R and the rods O O' disconnected, an equal number of rotations in direction of black arrow act to compress the cotton into the dimensions of a bale. The doors C being now opened, the bale may be bound in any approved way.

The follower may have a rod, O O', on each of two opposite sides, if desired, a duplication of the represented flanges being provided in the ring L.

The press may be fed by means of an endless apron.

By a press of this construction three hands and one horse have easily made a bale in the time which under the ordinary system seven men and two horses would occupy in packing only. The labor of stamping, so injurious to the lungs of the operatives, is entirely superseded by a far more effectual appliance. The common modes require a motion of ten feet and a corresponding bulk of press to do the work.

here performed within the space of four feet. What I claim as new and of my invention herein is—

1. In combination with the nut-screw and piston of a cotton or hay press, the described or a substantially equivalent arrangement of inclined planes $M M'$, operating to elevate and depress the follower N during the retrograde rotation of the screw, substantially as and for the purpose set forth.

2. The combination of the follower N and rod $O O'$, constructed and operating in connection with the inclined planes $M M'$, substantially as set forth.

3. The flanges T , applied within the box to prevent the return of the cotton, as set forth.

4. The described construction and arrangement of self-supporting L-shaped doors $c c'$, for the purpose explained.

In testimony of which invention I hereunto set my hand.

HORATIO F. HICKS.
